CLAIM

The ornamental design for a mold for forming concrete circular stepping stones, as shown and described.

DESCRIPTION

FIG. 1 is a top perspective view of a mold for forming concrete circular stepping stones showing my new design from the top and one side;

FIG. 2 is a bottom perspective view thereof showing my new design from the bottom and the side opposite that shown in FIG. 1; and,

FIG. 3 is a cross section thereof taken along line 3—3 of FIG. 1.
